APPARATUS FOR DETERMINING PARAFFIN PERCENTAGES

Karl A. Fischer, Washington, D. C.

Application May 13, 1948, Serial No. 26,910

4 Claims. (Cl. 88—14)

(Granted under the act of March 3, 1883, as amended April 30, 1928; 370 O. G. 757)

1

The invention described herein, if patented, may be manufactured and used by or for the Government for governmental purposes without the payment to me of any royalty thereon.

This invention relates to apparatus for indicating the purity of crystallized material and more particularly to an electro-optical apparatus for determining wax percentages. The need for such determination is specifically applicable in plant processes for producing waxes either of a purified character as by evaporating methods or waxes as they are obtained from dewaxing oils of either a mineral or vegetable character.

Generally, such determinations are made by a technical and careful crystallization of waxes from solvents on the basis of weights and measures. This method of determination usually requires a time element which is not conducive to efficient plant production. Further, it has been found that for different waxes the crystalline formation even if carefully conducted on glass plates may vary due to orientation or other influence and thereby cause errors in the determination of paraffinic percentages.

Based on experimental data and careful microscopic examination it has been found that paraffinic crystals, in contrast to most other crystals, have no tendency to include oil or liquid. However, an oil or liquid may adhere to the outside faces of such crystals or may be contained within capillary spaces in a mass or body of such crystals. Accordingly, it has been discovered that by a uniform method of crystallization, such oil or liquid retention can be tested and measured on the basis of the color shade caused by the addition of oil or liquid soluble dye stuffs which may be crystallized with the paraffinic substance.

It is, accordingly, an object of this invention to provide an apparatus for electro-optically determining the paraffinic content of uniformly crystallized waxes.

Another object of this invention is to provide apparatus for uniformly crystallizing a contaminated wax film with a crystallizable dye stuff.

A further object of this invention is to provide a simple arrangement adaptable to easy attachment to a wax producing system for readily measuring the wax content of the product.

It is an additional object of this invention to provide means for forming a crystallized waxed body through which a light beam may be projected to operate a recording device and register the paraffinic content of the crystallized mass as wax percentage.

Other objects and advantages of the invention

2

will be apparent from the following description taken in connection with the accompanying drawings, in which,

Figure 1 is a diagrammatic illustration of apparatus for forming a body of uniformly crystallized wax; and,

Figure 2 is an optical system used with the apparatus disclosed in Figure 1.

Referring to the drawings, a molten wax material 10 is evenly fed, for example, from a wax purifying or dewaxing process (not shown) by conduit 11 into vat 12. The conduit 11 is encased in a steam jacket 13 and the vat 12 is encased in, or surrounded by, a steam jacket 14 fed by conduit 14'. These steam jackets 13 and 14 are maintained at suitable temperatures, depending upon the relative melting points of the wax material undergoing testing, to keep the wax flowing through conduit 11 and in a molten condition in vat 12.

By means of conduit 11' a dye stuff in the nature of a Sudan dye, as Sudan red, or alizarin-irisol blue or the like, readily soluble in mineral oils, vegetable oils and molten paraffin is introduced into conduit 11 in minute quantities, for example, to form a 0.1 per cent solution in vat 12. A force feed such as an oil injector or similar pumping device may be utilized with conduit 11'. The coloring agent may be introduced into the liquid flowing in conduit 11 by conduit 11' either in dry powder form, or dissolved in molten paraffin or oil, as preferred. The minute quantities of added coloring agent and vehicle, if used, do not materially affect the final qualitative results, other than as hereinafter indicated. If necessary, and as expected, the added oil or paraffin vehicle is in known amounts and may be taken into consideration for quantitative determinations. While the illustrated coloring agents are soluble in molten paraffinic material the solidified paraffin or wax excludes the coloring agent, and if no solvent impurity, as oil, is present it reassumes its powder form which is normally in such slight amounts as to be ineffective as to coloring in the final analysis.

Suitable wax overflow or outlet pipe 15 inclosed in steam jacket 16 is provided on vat 12 in order to maintain a proper level and outflow for excessive liquid wax which may be introduced by the conduit 11. Further vat 12 may be provided with an outlet drain (not shown) and the steam jacket 14 is provided with a conventional steam trap outlet 17.

Positioned adjacent the vat 12 is a thin glass disc 18 of approximately 1.0 millimeter thickness

mounted on and adapted to be rotated by shaft 18'. The shaft 18' is coupled by conventional gearing (not shown) to a suitable motor (not shown) which turns the edge portion of disc 18, at an approximate rate of 1 revolution in 5 minutes or more, and permits it to pass through the molten wax 10 enabling the edge portion of disc 18 to pick up a film 19 of approximately 0.1 millimeter thickness (shown in exaggerated form). The edge of disc 18 and film 19, as it moves out of the body of molten wax 10, passes jet 20 through which an air flow is forced, to cool and crystallize the crystallizable wax and dye contained in film 19. This air flow may be cooled by obvious means as refrigeration or the like to temperatures which will solidify and crystallize the wax exclusive of its dye content in the film 19.

As heretofore indicated the dye stuff introduced by conduit 11' is uniformly mixed, for example, by baffles 21 into molten wax 10 and its possible contaminants in which the dye is soluble, and the slowly turning disc picks up a film of wax containing a proportional dye content. The slow movement of disc 18 permits a time interval to lapse between the solidification or crystallizing stage and testing stage, hereinafter described, which establishes color equilibrium in the film 19. This color equilibrium requires a time lapse of five to ten minutes before proper results can be evaluated or determined as the color shade of dye stuff does not become immediately constant.

Thereby, the dissolved dye content of the wax is found to be in relation to its oil content in that, for example, by use of Sudan red, a wax material containing an excessive quantity of oil will be a bright red color. Waxes containing traces of oil will result in a slight pink color and oil-free waxes show evenly and faintly grey in color.

It will, therefore, be apparent that due to the solubility of dye in oil such graduations in color are measurable and such measurements will be indicative of the purity of the wax material.

This measurement or testing of the film 19 is provided for by the use of a light beam from source 22 which may be, for example, a light bulb of low voltage. The light source 22 projects a light beam through the collector lens 23, green color filter 24 and diaphragm 25 onto the crystallized wax body 19, at for example, point 26, the portion of the light beam which passes from the diaphragm 25 and is transmitted through the crystallized wax body 19 is in relation to the dye content and registers on a conventional photovoltaic cell 27.

The action of the photovoltaic cell 27 is in accordance with established principles of producing a current proportional to the light intensity received which is registered by microammeter 28 through conductor wires 29 and 30. The microammeter 28 is scaled in graduations to represent, according to the proportion of light transmitted, the percentage or purity of the molten wax.

As illustrated in the above example, a green filter 24 is used with a wax material containing a red color to produce a complementary effect. Further, for percentage determinations of low melting soft paraffins which must be examined at relatively low temperatures light ray heat blocking means, as a water cell or the like, may be inserted in the path of the light beam before it is transmitted through the film. In the event that the crystallized material has a high melting point an unfiltered white light may be passed to the crystallized film 18.

By the above described apparatus there is disclosed a plant control means which provides easy and ready determination of the percentage of wax or paraffinic purity of a wax material as it is produced in a wax purifying system or by the dewaxing of oils as practiced by the trade.

Further, it will be obvious that different plant conditions using or producing different waxes and oils will regulate and operate the apparatus on the basis of conditions and standards suitable to each.

For example, the process as disclosed and described is readily adaptable for qualitative determination in batch processing, as only periodic checks are necessary and the solidified film may be removed from disc 18 by remelting the solid in the molten solution 10 without resolidification until a new reading or determination is to be made. Otherwise, the solidified film may be removed from the disc 18 by suitable solvents. Normally, inflow of new molten paraffinic material and coloring agent through conduit 21 and outflow of tested material through conduit 15 will provide a change of molten solution in container 12 sufficient for general qualitative determinations of plant runs.

Having thus described my invention, it will be apparent that this method and apparatus may be utilized to the purposes and advantages above indicated in addition to being applicable for determination of the purity and clarity of crystallizable materials having characteristics equivalent to wax contaminated by solvents or other materials within which a crystallizable dye is soluble.

While the present crystallizing and testing arrangement has been described in considerable detail, it will be obvious that various minor changes may be made within the scope of the appended claims.

Reference is made to my copending application Serial No. 26,914, "Method of Testing Wax," filed May 13, 1948.

I claim:

1. Apparatus for measuring the purity of a normally solidified paraffinic body by color modification of the impurities contained therein, comprising a container, liquid feed means and liquid outlet means for said container, liquefying means for maintaining a solidifiable paraffinic body in liquid condition in said container, feed means connected to said liquid feed means for introducing into said liquid body a coloring agent which is soluble in said liquid body and insoluble in the solidified paraffinic component of said body, a transparent disc positioned above said container body and adapted to rotate its edge in the container which edge removes a film of the liquefied body adhering thereto, conditioning means for solidifying the film adhering to the edge of said disc, light means for measuring the coloring of said impurities by said coloring agent, and time delay means to provide color equilibrium in the solidified film between the initial solidification of the said film and the measuring of the coloring effect.

2. Apparatus for measuring the purity of a normally solidified paraffinic body by color modification of the impurities contained therein, comprising a container, liquid feed means and liquid outlet means for said container, liquefying means for maintaining a solidifiable paraffinic body in liquid condition in said container, feed means connected to said liquid feed means for introducing into said liquid body a coloring agent which is soluble in said liquid body and insoluble in the

solidified paraffinic component of said body, a transparent disc positioned above said container body and adapted to rotate its edge in the container which edge removes a film of the liquefied body adhering thereto, means for rotating said disc at a uniform slow speed, and photoelectric means aligned with the edge of said disc at a point remote from the point of egress of said disc from the contents of said container for measuring the coloring imparted by said coloring agent to the impurities in the film which solidifies on said disc during its rotation.

3. Apparatus according to claim 2, wherein said photoelectric means include a color filter of a color complementary to that of said coloring agent.

4. Apparatus according to claim 1, wherein said conditioning means comprise a cold air jet.
